William W. Thompson INVENTOR

BY

A. G. Burns ATTORNEY

UNITED STATES PATENT OFFICE.

WILLIAM W. THOMPSON, OF FORT WAYNE, INDIANA.

CLOTHESLINE HOOK.

Application filed August 4, 1922. Serial No. 579,611.

To all whom it may concern:

Be it known that I, WILLIAM W. THOMPSON, a citizen of the United States of America, and resident of Fort Wayne, in the 5 county of Allen and State of Indiana, have invented certain new and useful Improvements in Clothesline Hooks, of which the following is a specification.

This invention relates to improvements in 10 clothes line hooks and the object thereof is to provide a fastening for a clothes line, so constructed that the line by simple manipulation may be secured in a manner to prevent it from retracting when drawn tight, 15 and which will also admit of the detachment of the line by simple manipulation.

This object is accomplished by the construction illustrated in the accompanying drawings, in which:—

20 Fig. 1 is a side elevation of a clothes hook embodying the invention;

Fig. 2 is a front elevation projected from Fig. 1;

25 Fig. 3 is a perspective view showing the invention as it appears in use with a clothes line attached thereto;

Fig. 4 is a side elevation showing a modified form of the invention; and

30 Fig. 5 is a front elevation projected from Fig. 4.

The characters appearing in the description refer to parts shown in the drawings and designated thereon by corresponding characters.

35 The invention comprises a hook 1 formed of a metal rod, one end of which is securely fixed in a base 2. At the point 3 of the hook, the rod is bent and extends from the point in parallelism with and adjacent to the outer portion of the hook 1 down to the lowermost portion thereof where a pendant projection 4 is formed by folding the rod laterally upon itself. The outer terminal of the rod is bent so as to extend upwardly in conformity with the curvature of the hook and with slight lateral divergence, said outer portion forming a prong 5 adjacent the intermediate portion 6 of the rod.

40 The base 2 has a series of screw holes 7 for the application of screws in mounting the base.

45 In the form of the invention shown in Figs. 4 and 5 the hook 8 is formed of a metallic rod, one end of which is bent so as

to form a shank 9 which is screw threaded 55 so as to admit of its being screwed into a supporting post (not shown). At the point 10 of the hook the rod is folded laterally upon itself so that its portion 11 extends in parallelism with and adjacent to the hook 8, said portion extending past the shank 9 and being folded laterally upon itself forming a pendant projection 12, the upwardly extending terminal of the rod forming a divergent prong 13. In this form, the invention is constructed complete from a single piece of material.

50 In utilizing the invention the hook is mounted upon any suitable support in the customary manner and the clothes line 14 is applied by drawing it downwardly over the hook, around the front of the pendant projection 4 and then between the prong 5 and the intermediate portion 6 whereupon the line becomes wedged and thus held securely from retracting. In detaching the line, that portion thereof wedged behind the prong is drawn upwardly over the point of the prong and released so that the line extends loosely in the hook from which it may 55 then be easily removed. When the line is applied to the device in the manner illustrated in Fig. 3 and the ends of the rope are drawn taut, the line is wedged between the prong and the intermediate portion 6 and is also wedged between the hook 1 and the adjacent face of the pendant projection 4, thus doubly securing the line from slipping when pulled in either direction.

55 What I claim is:—

1. A clothes line hook formed of a metal rod, one portion of which is bent so as to form a hook, that portion contiguous to the point of the hook being folded so as to extend in parallelism with and adjacent to the outer portion of the hook, said contiguous portion extending beyond the lower portion of the hook and being folded so as to form a pendant projection, the outer terminal of said rod being curved upwardly forming a 100 prong adjacent to said contiguous portion.

2. A clothes line hook formed of a metallic rod, one end portion thereof forming a hook, the opposite end portion thereof forming a prong, and the intermediate portion thereof being contiguous with the point of the hook and the connected end of the prong, there being formed a pendant pro-

jection at the juncture of the intermediate portion and the prong, the outer portion of the hook, the intermediate portion and said prong extending in a plane in close proximity to each other in successive order so that when a clothes line is applied thereto the line may be wedged between the hook and the intermediate portion and also

between the intermediate portion and the prong. 10

In testimony whereof I affix my signature in presence of two witnesses.

WILLIAM W. THOMPSON.
